SELIM E. GROUT, OF WEST CONCORD, VERMONT.

Letters Patent No. 87,843, dated March 16, 1869.

IMPROVEMENT IN TOWEL-DRYERS.

The Schedule referred to in these Letters Patent and making part of the same.

To all persons to whom these presents may come:

Be it known that I, SELIM E. GROUT, of West Concord, in the county of Essex, and State of Vermont, have invented a new and useful or Improved Towel-Drier, for a stove-pipe or funnel; and do hereby declare the same to be fully described in the following specification, and represented in the accompanying drawings, of which—

Figure 1 is a top view, and

Figure 2, a side elevation of it.

The apparatus in question is to be applied to the upright part of a stove-funnel, and over a stove, it being for the purpose of supporting towels, clothes, or other articles for being dried or heated by the heat radiated from such funnel or stove.

In the drawings—

A denotes a sectional clamp, constructed in two halves, *a a*, formed as represented.

These two portions are to be hinged together at their rear ends, or are to be provided with screws, or other proper devices, for connecting and disconnecting them.

When fixed on a stove-funnel, such funnel goes through the circular opening *b* between such parts, they being held to the funnel by being clamped upon it.

Each of the said parts *a* supports a rail, or bent wire, *B*, which is arranged upon, and so as to extend above the said part at its front, in manner as shown in the drawings.

Each wire, or rail *B*, which is curved lengthwise, serves as the fulcrum for a series of radial levers, *C C*, each of which is applied to the rail, so as to be capable of being revolved or turned thereon, in order that the shorter arm of such lever may be caught under, as well as removed from, when necessary, one of a series of hooks, *D D D*, arranged and extended upward from the part *a*, in manner as represented.

Each of the hooks, when caught upon a lever, serves to hold it in, or about in, a horizontal position; but when the lever is out of connection with the hooked arm, such lever will fall into a vertical position, so as to cause the whole apparatus to take up less room, or be capable of being packed in less space, than it does when the levers are projected horizontally and radially from it.

To the front of one of the parts *a*, I usually apply a hook, *E*, on which an article, such as a stove-hook or plate-lifter, may be hung, as occasion may require.

I claim the combination and arrangement of the two series of levers *C C*, their supporting rails *B B*, the two series of hooks *D D D*, and the sectional clamp *A*, made in two parts, *a a*, so as to be clamped or applied to a stove-funnel, as described.

SELIM E. GROUT.
